US0D1045385S

(12) United States Design Patent (10) Patent No.: US D1,045,385 S
(45) Date of Patent:  Oct. 8, 2024

(54) HANDBAG

(71) Applicant: Bottega Veneta S.R.L., Montebello Vicentino (IT)

(72) Inventor: Matthieu Blazy, Milan (IT)

(73) Assignee: Bottega Veneta S.R.L., Montebello Vicentino (IT)

() Term: 15 Years

(21) Appl. No.: 29/848,799

(22) Filed: Aug. 5, 2022

(30) Foreign Application Priority Data

Feb. 25, 2022 (EM) 008871693-0002

(51) LOC (14) Cl. 03-01

(52) U.S. Cl.
USPC D3/244

(58) Field of Classification Search
USPC D3/232, 233, 239, 244-246, 277, 301, D3/303-306
CPC A45C 3/06; A45C 3/00; A45C 7/0063; A45C 13/08; A45C 3/04

See application file for complete search history.
